UNITED STATES PATENT OFFICE.

SIMON MORRISON, OF BROOKLYN, NEW YORK, ASSIGNOR TO AUGUST GOERTZ & COMPANY, INC., OF NEWARK, NEW JERSEY, A CORPORATION OF NEW JERSEY.

VANITY CASE.

Application filed January 25, 1923. Serial No. 615,445.

To all whom it may concern:

Be it known that I, SIMON MORRISON, a citizen of the United States, residing at Brooklyn, in the county of Kings and State 5 of New York, have invented certain new and useful Improvements in Vanity Cases, of which the following is a specification.

My said invention relates to an improved vanity case and it is an object of the same 10 to provide a case which shall be more convenient in use than those hitherto employed.

Referring to the accompanying drawings, which are made a part heretof and on which similar reference characters indicate similar 15 parts,

Figure 1 is a perspective of my device viewed from the front,

Figure 2 a similar view of the device with the parts in a different position, and

Figure 3 a vertical central section of Figure 1.

In the drawings reference character 10 indicates a lower compartment having a transversely extending partition 11 with one or 25 more cut-out portions forming openings to hold toilet articles. In this instance a single opening is shown in which is located a downwardly extending rim 12 resting at its lower edge on the bottom of the container 10. A compact of rouge or the like comprising a bottom plate 13 of glass or other suitable material and a cake 14 fast thereto is located within the rim and rests against the bottom wall of the container.

The middle section of the vanity case consists of a container 15 preferably of metal secured to the partition 11 by a U-shaped member 16, the body of the member being hinged to the partition 11 and the extremities of the legs being hinged to the bottom of the container 15 near opposite edges thereof. A compact carrier in the middle compartment comprises a glass plate 17, a compact 18, and a ring 19 of sheet metal 40 having an edge bent up to cover the edge of the glass and having projections 20 some of which are bent over the edge of the compact to hold it and the glass in place and others of which are bent out to engage a bead at 21 on the compartment, thus holding the compact carrier in place. The bottom of the middle compartment is cut away to expose the glass as shown in Figure 2 and this glass is silvered at the side next to the

50 compact to form an effective mirror.

The cover 22 is hinged to the middle compartment and contains a mirror 23. At the side opposite the hinge I provide a punched out part 24 to coact with one side of a double latch 25 carried by the central compartment and held in place by a spring. The latch is provided with a finger piece 26 for forcing it back as explained more fully in my prior Patent No. 1,501,798, dated July 15, 1924. The bottom compartment 60 also has a punched out portion 27 to coact with the other part of the double latch. At the back of the bottom compartment is another punched out offset 28 which serves as a means by which the bottom compartment can be held down while the top and cover are lifted away from it so as to expose the mirror by tilting the parts in the opposite direction to that indicated in Figure 2. This is also a convenient method of exposing the mirror when only a single mirror is used, the one at 23 being omitted in some instances.

Figures 1 and 3 show one position which the parts may assume. In this position the cosmetics carried in the bottom and intermediate compartments are so presented as to be available to the user. If it is not desirable to use the material in the central compartment at any time the cover may 70 remain closed and this with the intermediate compartment may be lifted away from the bottom compartment and tilted backward so as to expose the mirror through the bottom of the intermediate compartment. 75 It will be seen that the device in the position shown in Figures 1 and 3 can be held conveniently in the hand and if the parts are of ordinary size will be substantially concealed. This is true to a still greater extent when used as indicated in Figure 2.

Various modifications will be obvious to those skilled in the art and therefore I do not limit myself to what is shown in the drawings and described in the specification but only as indicated in the appended claims.

Having thus fully described my said invention, what I claim as new and desire to secure by Letters Patent, is:

1. A vanity case comprising a lower section, a middle section forming a closure therefor, an upper section hinged to and forming a closure for the middle section, and a connecting bar securing the lower and mid-

- 2
- dle sections together so that latter may be lifted and offset from the former, each section being adapted to contain toilet articles, and all arranged to face toward each other 5 when in position for use, substantially as set forth.
2. The combination in a vanity box of a bottom compartment, a middle compartment adapted to nest therein, and a cover hinged 10 to and fitting over the middle compartment and containing a mirror, said bottom and middle compartments being adapted to contain cosmetics, a link connection, one end of said link connection being pivotally connect- 15 ed with said bottom compartment, and the other end of said link connection being pivotally connected with said middle compartment, substantially as set forth.
3. In a vanity case, a lower compartment, 20 a middle compartment, a mirror exposed through the bottom of said middle compartment, a link connection fulcrumed on said lower compartment, said middle compartment being pivotally connected with the free 25 end of said link connection so that it may be both lifted away from said lower compartment and tilted relatively thereto to render said mirror visible, substantially as set forth.
4. A compact carrier for vanity cases comprising a sheet of glass silvered at one side 30 and a compact secured to the silvered side of the glass, substantially as set forth.
5. In a toilet article, a mirror, a powder compact, and means securing them perma- 35 nently to each other, substantially as set forth.
6. A vanity case comprising a bottom com- 40 partment, a middle compartment, a cover for the latter, a mirror in the cover, a hinge con- 45 necting the cover to the middle compartment said middle compartment being adapted to nest in the bottom compartment, and a bar hinged to the middle compartment approxi- 50 mately midway between two sides thereof 55 and to the bottom compartment near one side thereof whereby said parts when opened may face in the same direction or away from each other, substantially as set forth.
7. A vanity case comprising a bottom com- 60 partment, a partition parallel to the bottom of the compartment and having an opening, a compact held in said opening, an inter- 65 mediate compartment, said intermediate compartment having a circular opening 70 in its bottom, a cover for the intermediate compartment, a mirror facing said circular opening, a U-shaped bar hinged be- 75 tween its ends to the partition in the bottom compartment and hinged at its ends to the intermediate compartment at opposite sides 80 of said opening the inner curve of the U-shaped bar conforming to the lower part of the opening, substantially as set forth.
8. A vanity case comprising a lower con- 85 tainer for holding cosmetics, a middle con- tainer having a mirror facing toward the lower compartment, an upper container forming a cover for the middle container and hinged thereto, one of the latter containers holding a second mirror and the other hold- 90 ing cosmetics, whereby either mirror may face toward the user together with at least one of the containers for cosmetics, substan- tially as set forth.
9. A vanity case comprising a circular con- 95 tainer for cosmetics, a circular closure there- for holding a mirror facing toward the con- tainer when the case is closed, and a connect- 100 ing bar hinged to both said parts at different distances from their centers whereby the cover may swing across the container into two different open positions, substantially as set forth.
10. In combination with a box adapted to contain a rouge-compact, or the like, a car- 105 rier-frame pivotally connected with said box, a second box, and a means of pivotal connec- 110 tion for pivotally connecting said second box to said frame.
11. In a container of the character de- 115 scribed, a main compartment and a member fitted therein having an auxiliary comp- 120 artment hinged thereto.
12. In a receptacle of the character de- 125 scribed, a compartment, a container associ- 130 ated with said compartment, a connection fulcrumed on said compartment to the free 135 end of which said container is pivoted, said connection normally lying between the bot- 140 tom of said container and the top of said 145 compartment, and said connection permitting off-set separation of the compartment and container when the receptacle is in use.
13. In a device of the character described, 150 a compartment, a container, and a member 155 normally lying in substantially parallel plane between the compartment and con- 160 tainer and pivotally connected thereto.
- In witness whereof, I have hereunto set my 165 hand and seal at New York, New York this 23d day of January, A. D. nineteen hundred and twenty-three.

SIMON MORRISON. [L.S.]
